UNITED STATES PATENT OFFICE.

THURIBE GELINAS, OF MANCHESTER, NEW HAMPSHIRE.

SHOE BINDING.

Application filed May 20, 1925. Serial No. 31,622.

This invention relates to improvements in shoe bindings and has for its principal object to provide a binding for the edges of the upper and the straps of women's shoes.

In the manufacture of women's shoes of a very good quality, it is customary to form what is known as a "French cord" edge on the edges of the upper and the strap. The method by which a "French cord" edge is usually formed involves considerable expense as well as considerable time. One of the important objects of the present invention is to provide an imitation "French cord" edge which will present a neat and attractive 15 appearance when attached to a shoe, the shoe binding embodying my invention being very inexpensive, and further of such construction as to facilitate the securing of the same very easily and readily on a shoe.

A still further object is to provide a shoe binding of the above mentioned character which may be attached to the edges and the straps in such a manner as to cause no discomfort to the wearer, the binding being 20 strong and durable, and otherwise well adapted for the purposes for which it is designed.

Other objects and advantages of the invention will become apparent during the course 30 of the following description taken in connection with the accompanying drawing.

In the accompanying drawing forming a part of this application, and in which like numerals designate like parts throughout the 35 views:

Figure 1 is a side elevation of a lady's shoe showing my improved shoe binding associated therewith.

Figure 2 is a fragmentary enlarged side 40 elevation of the shoe binding attached to the upper edge of the upper of a shoe with parts broken away to illustrate the cord, and

Figure 3 is a vertical section taken approximately on line 3—3 of Figure 2.

In the drawing wherein for the purpose of illustration is shown the preferred embodiment of my invention, the numeral 1 designates generally my improved shoe bind-

ing, the same comprising the ordinary galloon, flat tape, or ribbon 2. The galloon is folded longitudinally, and adapted to be disposed within the fold is the cord 3.

The folds 4 and 5 respectively of the galloon 2 are adapted to extend over the upper edge of the upper A of a lady's shoe as well as over the edges of the strap thereof. In this manner, the fold 4 will be disposed adjacent the inner side of the leather material from which the upper A is formed while the fold 5 will be disposed adjacent the outer sides of the upper, as is more clearly illustrated in Figure 3.

The cord 3 will also be disposed on the outer side of the material from which the upper A of the shoe is formed, and is preferably arranged adjacent the upper edge of the upper. This is also more clearly illustrated in Figure 3. With the parts of the shoe binding as above described disposed over the edges of the upper and straps of a shoe, the folds of the binding are stitched to the material forming the upper as well as the straps by the stitching illustrated at 6. The stitching 6 will hold the cord 3 in proper position adjacent the upper edge of the upper so that the shoe binding will form a beaded, or rounded edge, projecting from the outer side of the upper as well as the straps of the shoe adjacent the edges thereof, thus giving the appearance as the form of the "French cord" edge which has heretofore been used in finishing the edge of women's shoes of a high grade quality. By forming the bead on the outside of the material from which the upper and straps are formed, adjacent the edges thereof, the shoe bindings will in no way cause any discomfort to the wearer. A shoe binding of the above mentioned character may be easily and readily attached on a shoe and will furthermore be very inexpensive.

While I have shown the preferred embodiment of the invention it is to be understood that minor changes coming within the field of invention may be resorted to without departing from the spirit of the invention or the scope of the appended claim.

Having thus described the invention, what I claim as new and desire to secure by Letters Patent is:—

A shoe binding comprising a galloon folded longitudinally over the upper edge of the upper of the shoe, the folds being stitched to the opposite sides of the upper, and a cord disposed within the folded galloon between

the outer side of the upper and the outermost fold, the cord being further disposed between the folded portion of the galloon and the stitching and extending longitudinally along the upper, adjacent the upper edge thereof to provide a rounded or beaded edge. 10

In testimony whereof I affix my signature.
THURIBE GELINAS.
